RAZOR STROP AND STERILIZER

Stanley Browning, Cynthiana, Ky.

Application May 15, 1943, Serial No. 487,163

2 Claims. (Cl. 51—268)

The invention has for an object to provide means for protecting razor strops from dust and the like, and also for improving the sanitary conditions incident to the operation of public barber shops as well as for private users, by assuring the effective sterilization of the strops.

It is an important aim of the invention to provide an automatic means for retaining a strop within a protective casing and sterilizing chamber, but permitting its immediate and ready withdrawal at any time for use, and also to provide for its automatic retraction when not in use.

A further important aim of the invention is to provide a construction in such an article which may be readily produced at a low cost, and which may be mounted in various convenient locations.

It is a special aim of the invention to present the invention in a construction which adapts it to be incorporated in the arm of a barber's chair, so that no special space will be occupied by the device. It is an important aim of the invention also to enable the incorporation of this device in the arm of a chair and, at the same time, have the strap in a convenient position for use, approximately at the same level and general location as now commonly practiced in barber shops. It is also an important aim of the invention to evolve a simple construction of the traction means of a highly efficient nature which will enable the full retraction of the strop within the case, without requiring strop to be bent, and yet requiring an enclosure comparatively short in comparison to the length of the strap, as well as occupying little room otherwise.

Additional objects, advantages and features of the invention reside in the construction, arrangement and combination of parts involved in the embodiment of the invention, as will be more clearly apparent from the following description and accompanying drawings, wherein

Figure 1 is a top view of the mechanism, with the upper part of the casing removed and with certain other parts broken away, to show the tackle or strap retraction means.

Figure 2 is a vertical longitudinal sectional view of the device.

Figure 3 is a rear end view of the device.

Figure 4 is a front end view thereof.

Figure 5 is a fragmentary perspective view showing the anchorage for the retraction spring, 50 and with the sliding carriage and pulley block device thereon.

There is illustrated a case 10, which in the present instance is embodied in a general form of the arm of a barber's chair, including a base 55

plate 11, and a cover 12, the latter including enclosing side and end walls resting upon the plate 11, so as to form a complete elongated chamber and enclosure. The forward end of the case cover is formed with a customary knob 13, which is slightly raised and affords a convenient grip for the hands of a barber's patron, the adjacent ends of walls being a continuation of the knob portion and extending downwardly to the plate 11, as at 14, in Figure 2 and Figure 4. The rear end wall 15 of the case cover is simple and planiform, extending downwardly to the plate 11, as shown in Figure 2. The cover 12 is preferably secured to the plate 11 removably by means of suitable fastenings, as indicated at 16, or otherwise. The end wall 15 is formed with a transverse horizontal slot 17 of suitable dimensions to permit the free sliding movement of a razor strop 18 therethrough.

The case as described may be mounted upon the usual supports for the arm of a barber's chair, in any conventional way customarily followed or approved in the construction of such apparatus, these details not being illustrated, as being no novel part of the invention.

Four stud posts 18 are erected upon the plate 11, two adjacent each end of the casing, those at the rear end being utilized as fastenings for a transverse angle plate anchor 19, to be subsequently described. Supported upon the posts 18 there is a strop supporting foraminous plate 20, of any suitable material by which the strop 18 is supported in the upper part of the chamber, close to the top of the case 12.

The strop 18 is of conventional construction well understood, and is formally illustrated in Figures 2 and 3, the strop being provided with a handle 21 attached by suitable terminal reinforcement 22 to the end of the strop proper, these last named parts remaining outside the case at all times, and the handle hanging, as shown in Figure 3, conveniently to be grasped for withdrawal of the strop, at any time.

At the opposite end of the strop, a transverse plate 23 of metal or other material of suitable strength is incorporated in the end of the strop, and this is connected by means of a ring or link 24 to a cable or cord 25 by which the strop is drawn into the case. This cable passes around a pulley 26 mounted in a suitable standing sheath case 27, mounted upon the plate 11 close to the extreme end of the case 12. A sliding carriage 28 is movable longitudinally in the case below the plate 20, and has mounted on its upper side two sheaths 29. The carriage or sheaths have ex-

tended therefrom a transverse draw-bar 30, and connected between the bar and the anchor plate 19 there is a plurality of contractile helical-springs 31 tending to draw the carriage rearwardly into close relation to the anchor 19. A standing block 32 is mounted upon the plate 11 at one side of the sheath case 27, and the cable 25, after passing around the pulley 26, is extended rearwardly and around the upper of the pulleys 29, thence forwardly and through the block 32 thence rearwardly and around the lower of the pulleys 29 and forwardly to an anchor pin or rivet 33, by which it is secured to the plate 11.

It will thus be seen that movement of the carriage 28 converted and transmitted to the end of the strop is multiplied four times, and movement of the strop transmitted likewise to the carriage is reduced correspondingly, so that complete withdrawal of the strop will involve only a slight movement of the carriage, and correspondingly the return movement of the carriage by the springs 31 will complete the retraction of the strop, as may be desired.

A container 34 of any suitable vapor evolving or sterilizing or antiseptic material is mounted upon the under side of the case 11 in the present instance, although it may be otherwise located if desired, its present location being midway of the length of the case 10. This comprises a ferrule or ring 35 permanently secured to the under side of the case 11, and a cap or container portion proper 36, which may be screwed upon the ferrule. The plate 11 is formed with a multiplicity of apertures 37 therethrough, within the boundaries of the ferrule 35, so that vapors evolved from the materials within the container may pass upwardly through the openings 37 and become diffused within the case 12, so as to maintain a proper sterile condition in the strop 18.

In order to permit ready access to the tackle including the cable and the pulleys, the plate 20 is preferably mounted removably upon the posts 18', the posts having extended threaded parts to receive nuts 38, as indicated in Figure 5, the nuts serving to hold the plate upon the upper end of the posts, which are formed with suitable shoulders for the purpose.

In the use of the invention, a suitable vapor evolving antiseptic or sterilizing material being introduced into the receptacle 34, and a strop 18 being connected as indicated, as long as the strop is retained within the case, it will be subjected to the vapors evolved therein and maintained in a good sanitary condition.

When it is desired to use the strop, the barber merely grasps the handle 21, and draws the strop out as far as required for use. The slot 17 is preferably shaped or of a size to permit passage of the rings 24 outwardly therethrough, so that the strop may be rotated on its longitudinal axis, 55

to present either side upwardly for use of a razor thereupon in the customary fashion involved in stropping of a razor, as is well understood.

While I have described the embodiment of my invention with great particularity, it will, nevertheless, be understood that this is purely exemplary, and that various modifications in the construction, arrangement and combination of parts, substitution of materials and mechanical equivalents may be made therein without departing from the spirit of the invention, except as more specifically set forth in the appended claims.

I claim:

1. A device of the character described comprising an elongated case to contain in extended form the major portion of a conventional razor strop, and being slotted at one end for the passage of said strop therethrough longitudinally, a spring-loaded carriage longitudinally reciprocable in the case, the spring normally holding said carriage retracted to one limit of its movement, a razor strop engaged in the case, a tackle connected between an end of the strop and said carriage, including motion-multiplying block and cable, a foraminous separator plate being mounted in the case between the strop and said tackle, and a container of vapor-producing sterilizing material connected with the case and having communication with the interior thereof, said strop having a handle normally exposed externally of the case, for the purposes described.

2. A device of the character described, comprising a base plate and a cover set thereon, said cover being of elongated form and of a length to contain in extended shape the major portion of a conventional razor strop, said case having a horizontal transverse slot at one end, a razor strop engaged slidably therethrough, said strop having a handle outwardly exposed of the case, a foraminous separator plate in the case below the strop, a carriage longitudinally reciprocable in the case below the separator plate, spring means anchored upon the base plate and connected to the carriage for retention of the carriage to one limit of its movement, a central standing sheath block, a cable engaged with the strop and passing around said sheath, pulleys upon said carriage and base plate receiving said cable therearound in motion-multiplying relation to the carriage, said cable being anchored to the case at its inner extremity, said base plate being centrally apertured, and a container mounted upon the under side of the plate in communication with the said openings through the plate, whereby disinfectants, antiseptics, or the like, vapor-producing materials in the container may effect sterilization of a strop within said case.

STANLEY BROWNING.
